UNITED STATES PATENT OFFICE.

WILLIAM J. YOUNG, OF CLEVELAND, OHIO, ASSIGNOR, BY DIRECT AND MESNE ASSIGNMENTS, TO FRANK C. FELLER AND WILLIAM J. SPRINGBORN, OF SAME PLACE.

LIQUID-CARBONATING APPARATUS.

SPECIFICATION forming part of Letters Patent No. 681,526, dated August 27, 1901.

Application filed August 31, 1900. Serial No. 28,672. (No model.)

To all whom it may concern:

Be it known that I, WILLIAM J. YOUNG, a citizen of the United States of America, and a resident of Cleveland, in the county of Cuyahoga and State of Ohio, have invented certain new and useful Improvements in Liquid-Carbonating Apparatus, of which the following is a specification.

My invention relates to improvements in apparatuses for carbonating liquids; and the object of my improvement is to provide for an apparatus which is simple in construction, convenient in point of manipulation, and efficient in point of operation. I attain this object in an apparatus constructed substantially as shown in the accompanying drawings, in which—

Figure 1 represents a vertical sectional view of said apparatus complete. Fig. 2 is an enlarged sectional view of a part thereof. Figs. 3 and 4 illustrate plan views of parts thereof detached.

Like letters of reference denote like parts in the drawings and specification.

The vessel part of this apparatus consists of the tank A and the column B, of which the latter has secure connection with the top part of the former. (See Fig. 1.) The tank proper is provided with suitable valves *a* and a gage-glass *b*. At an outlet is provided from said tank. *d* and *e* are inlet-pipes to said column, respectively, for gas and liquid, while by means of the pipe C auxiliary open relation is established between the top of the tank and that of the column. Inside the column, upon a rod or tube, are mounted a series of cones E and bowls F, also a valve G, (see Figs. 1 and 2,) and the rod itself is suitably supported near the foot of the column, as at *f*. The outer surface of the cones, as well as the inner surface of the bowls, is undulated or flanged in terrace-like form. (See Figs. 2, 3, and 4.) As shown, these flanges are superimposed and form annular dripping-flanges, the drippings from one flange passing into the next flange below it. This is of positive advantage in a device of this character in view of the fact that there is not only a continuous breaking up or atomizing of the liquid and enabling the molecules

to more readily absorb the gas, but in addition the liquid in breaking forms what might be termed a "curtain" from one flange to another, the successive curtains being of a different diameter, both sides of which are exposed to the action of the gas, and as each flange is either larger or smaller in diameter than the preceding one the succeeding curtains are of different character, the flanges of small diameter having a comparatively continuous curtain, while as the flanges gradually increase in diameter the curtains become more broken in continuity, it being understood that the amount of liquid dripping from one flange to another (after the flanges have become filled) is substantially the same, the difference in the circumference of the dripping edges of the flanges causing the change in the character of the curtain. This change in the character of the curtains is advantageous in that there is a better opportunity for the liquid to absorb the gas as the drippings become more divided in form, while the gradually diameter-increasing flanges again gradually bring the curtain to its initial form, followed by the gradually-increasing division due to the increase in size of the flanges. These continual changes tend to change the relative position of the molecules, giving them a thorough mixture, so that there is a more thorough absorption of the gas. This would not be possible were the cones and bowls provided with plain surfaces, as in such case the one side of the liquid sheet is not permeable by the gas, and hence there is not only less tendency for the rapid absorption of the gas, but this assimilation is retarded by the movement in a body of the liquid over such plain surface. Normally the valve G is held against the face of nozzle *g* which projects inwardly from cover *h* of column B. Preferably a spring *i* is interposed between the head of said valve and the terminal of said tube D, which receives the stem *j* of said valve, as seen in Fig. 2. As shown, an ordinary stop-valve *k* is secured to the outside of the cover, connected with which is pipe *e*, wherein liquid is conveyed to said apparatus. Both the liquid in pipe *e* and carbonic-acid gas in pipe *d* are supplied under pressure,

the liquid-pressure being higher than the gas-pressure. The flow of liquid into column B is automatically controlled by means of valve G, from where it collects in tank A. As the 5 tank A and the carbonating chamber or receptacle B are necessarily gas-tight, the continued supply of gas within the chamber will gradually cause the increase of pressure within the chamber and the tank (both being under 10 the same conditions, owing to the presence of the pipe C) until this pressure is greater than that of the liquid, whereupon the valve G will close and cut off the supply of liquid to the chamber and at the same time substantially stop the flow of gas into the chamber, by reason of the greater pressure existing therein. When this pressure is reduced 15 by the withdrawing of some of the contents from the tank, the liquid-pressure then being greater than the pressure within the chamber will force the valve G open and allow liquid to enter until this pressure is again secured. It will be readily understood that this increase of pressure in the tank and chamber is due to the gradual increase of the liquid 20 in the tank, the surface of the liquid therein acting somewhat in the nature of a piston to compress the gas of the tank and chamber, so that when this is reduced by 25 lowering the surface of the liquid in the tank the valve G will be opened, said valve operating under the greater pressure in an obvious manner. It will therefore be seen that I have provided an apparatus in which the 30 passage of the liquid into the carbonating-chamber is controlled solely by the pressure formed within the chamber itself, and therefore there is no requirement of auxiliary controlling devices located without the chamber, 35 dispensing entirely with mechanism which 40 will in itself control the passage or the pressure of the liquid to the chamber. In fact, a device of such a character would practically defeat the object in that there is required a constant and substantially unvarying pressure of both liquid and gas. The liquid in passing through valve G is first 45 caught in the upper trough of the uppermost bowl. Thence it overflows into the second 50 and third trough, from where it flows over troughs of the next following cone. Thence it meets another troughed or flanged bowl, and so on until it drips over the last disk l or whatever obstruction may be placed in its path. 55 Liquids thus being thoroughly atomized or agitated can and will take up all the gas they are capable of absorbing, and since there is an auxiliary equalizing-pipe C provided for no trapping of gas can occur; but all incoming gas from pipe d is allowed to ascend freely 60 in column B for being commingled with and absorbed by the falling liquid. As often as carbonated liquid is withdrawn from tank A the pressure therein becomes reduced, whereupon a fresh supply of water will enter by 65 way of valve G to be carbonated in the manner as above described. Since the larger area

of the valve G is exposed to the gas-pressure, it is evident that the latter should be supplied in sufficiently-reduced state in order to 70 maintain the valve G on the verge of opening to replenish water in sufficient quantity for absorption of the gas which is continually supplied at or near the bottom of the column.

What I claim, and desire to secure by Letters Patent, is—

1. A liquid-carbonating apparatus having a liquid-supply and a gas-supply each normally under constant pressure; and means located entirely within the carbonating-chamber of the apparatus for automatically controlling the entrance of liquid into said apparatus by the variations in pressure within the apparatus, the gas-entrance being free from controlling means other than the pressure within the chamber. 80

2. A liquid-carbonating apparatus having a liquid-supply and a gas-supply each normally under constant pressure; and a valve located entirely within the carbonating-chamber of the apparatus controlled by the variations in pressure within the apparatus for governing the entrance of liquid into said apparatus. 90

3. In a carbonating apparatus, a carbonating-chamber; a gas-inlet thereto; a liquid-inlet at the upper end thereof; and means located within said chamber actuated by the liquid and gas pressures respectively for controlling the passage of the liquid through said inlet. 95

4. In a liquid-carbonating apparatus, a carbonating-chamber; a gas-inlet thereto; a liquid-inlet at the upper end thereof; and a spring-pressed valve located within said chamber actuated by the liquid and gas pressures respectively for controlling the passage of the liquid through said inlet. 105

5. A liquid-carbonating apparatus having a tank; a carbonating-chamber; a gas-inlet 110 and a liquid-inlet to said chamber, the liquid-inlet being controllable by the variations in pressure within said tank and chamber; and means for retaining the pressure in said chamber in equilibrium with the pressure in the tank. 115

6. A liquid-carbonating apparatus having a tank; a carbonating-chamber; a gas-inlet and a liquid-inlet to said chamber, the liquid-inlet being controllable by the variations 120 in pressure within said tank and chamber; and a pipe connecting said chamber and tank for holding the pressures therein in equilibrium relatively to each other. 125

7. In a carbonating apparatus for liquids, 125 a tank and column combined, the said column containing a series of flanged bowls and cones arranged alternately one above the other, an automatically-operating pressure-controlled inlet-valve for the water located 130 above the highest bowl and a gas-inlet below the lowest cone, an auxiliary pressure-equalizing pipe for said column and tank and an outlet from said tank all constructed and ar-

ranged substantially as and for the purpose set forth.

8. In a liquid-carbonating apparatus, a carbonating-chamber; a gas-inlet thereto; a liquid-inlet at the upper end thereof; and a valve located within the carbonating-chamber and having a diameter greater than that of the liquid-inlet and adapted to be seated against the periphery thereof, said valve being controlled by the variations in pressure within the apparatus for governing the entrance of liquid into said apparatus.

9. In a liquid-carbonating apparatus, a carbonating-chamber; a gas-inlet thereto; a liquid-inlet at the upper end thereof; and a valve located within the carbonating-chamber, said valve being concavo-convex and of greater diameter than that of the liquid-inlet and adapted to be seated against the periphery thereof, said valve being controlled by the variations in pressure within the apparatus for governing the entrance of liquid into said apparatus.

10. In a liquid-carbonating apparatus, a carbonating-chamber; a gas-inlet thereto; a liquid-inlet at the upper end thereof; an automatically-operating pressure-controlled valve located within the carbonating-chamber adapted to deliver the liquid in annular drippings; and a series of independent atomizing devices each having a plurality of superim-

posed annular dripping-flanges of varying diameter, adapted to receive and successively pass the liquid through the carbonating-chamber of the apparatus, whereby the liquid will pass through the carbonating-chamber solely in the form of drippings.

11. In a liquid-carbonating apparatus, a carbonating-chamber; a gas-inlet thereto; a liquid-inlet at the upper end thereof; a concavo-convex valve located within the carbonating-chamber and having a diameter greater than that of the liquid-inlet and adapted to be seated against the periphery thereof, said valve being controlled by the variations in pressure within the apparatus for governing the entrance of liquid into said apparatus; and a series of independent atomizing devices, comprising cones and bowls arranged alternately, each having a plurality of superimposed annular dripping-flanges forming annular cup-shaped portions, the drippings from one flange passing directly into the cup of the succeeding flange whereby the liquid will pass through the carbonating-chamber solely in the form of drippings.

Signed at Cleveland, Ohio, this 25th day of August, 1900.
